CLAIM

The ornamental design for a fence panel, as shown and described.

DESCRIPTION

FIG. 1 is a top plan view of a fence panel;

FIG. 2 is an enlarged view of the fence panel top section, taken from a line marked as 2 in FIG. 7, showing a front elevational view of that top section;

FIG. 3 is a bottom view of the fence panel;

FIG. 4 is an enlarged view of the fence panel top section, taken from a line marked as 4 in FIG. 8, showing a rear elevational view of the top section,

FIG. 5 is a right-side elevational view of the top section shown in FIG. 2;

FIG. 6 is a left-side elevational view of the top section shown in FIG. 2;

FIG. 7 is a front elevational view thereof of a complete fence panel, showing my design. The broken line marked with number 2 shows the portion represented in FIG. 2;

FIG. 8 is a rear elevational view thereof. The broken line marked with number 4 shows the portion represented in FIG. 4; and,

FIG. 9 is a rear view of the fence panel, assembled to other fence panels (in broken lines).

The broken lines represent environmental structure and form no part of the claimed design.
